Attn:

UNITED STATES PATENT OFFICE

CARL H. NORDELL, OF CHICAGO, ILLINOIS

DOOR OR SCREEN AND FASTENING MEANS

Application filed August 18, 1930. Serial No. 475,971.

The present invention relates to doors or screens and has for its object to produce a simple and novel device of that kind which shall present the appearance of a curtain hanging in folds.

In carrying out my invention, I employ a core member in the form of a frame covered on one or both faces with curtain material secured thereto; the frame being of such contour that when the curtain is attached thereto and follows the contour thereof it will have the appearance of hanging in folds. The top and bottom of the device should resemble an ordinary curtain and therefore the covering material should be secured to the frame in such a manner as to leave free upper and lower marginal portions thereon and at the same time make it possible to draw the covering taut.

Therefore, viewed in one of its aspects, the present invention may be said to have for its object to produce a simple and novel fastening means between a curtain and a supporting element or, since such fastening means may be used for other purposes, to produce a simple and novel fastening between two members in general.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is an elevation of a door or screen made in accordance with the present invention, parts being broken away; Fig. 2 is a section on a larger scale on line 2-2 of Fig. 1; Fig. 3 is a section on line 3-3 of Fig. 1, on the same scale as Fig. 2, the metal portion of the door or screen being broken away; Fig. 4 is a section on line 4-4 of Fig. 1, on the same scale as Figs. 2 and 3, only a fragment of the structure being shown; and Fig. 5 is a sectional view, corresponding to Fig. 3, on a larger scale and omitting the curtain or covering.

The door or screen comprises a core shaped to give and hold the desired form, the broad

faces being in waves similar to the vertical folds into which the curtain or other flexible sheet will lay itself when suspended in a laterally contracted condition; together with the flexible covering for one or both sides of the core member. In the arrangement shown, the core is in the form of a frame comprising two tubular uprights 1 and 2 connected at the top by means of cross pieces each of which is composed of two comparatively wide strips of sheet metal 3 and 4, each bent into the form of a series of waves succeeding each other from one end of the strip to the other. The two elements of each transverse frame member are secured by welding or otherwise to the vertical or upright frame members. If body or thickness to the door or screen be desired, the two elements of each transverse frame member may be held apart at the points that come nearest each other by means of spacers 5. Near the upper edge of each element of the upper cross piece, and near the lower edge of each element of each lower cross piece is a series of holes extending through the metal, these being preferably in the form of narrow transversely elongated slots 6. These holes or slots are spaced and distributed in any manner most suitable for each particular kind of fabric covering and the appearance which the stretched covering is to have. It will be understood that there will be four rows of holes only when the covering is extended across both sides of the frame as there need be no holes on a side that is not to be covered. The frame is covered in whole or in part by means of a flexible sheet 7 of curtain material or other suitable material that may be hemmed at the top and bottom, as indicated at 8; the flexible sheet being wrapped around the frame with the hems projecting above the top and below the bottom. To the flexible cover, adjacent to each of the slots in the frame, I have sewed on the inner side thereof a strong tape 9 that is carried up or down, as the case may be, to and past the corresponding outer edge of the member 3 or 4 and is then threaded through the adjacent slot 6 and has its free end pulled inwardly between the body portion of the tape and the face of the frame.

100

member. It will be seen that when the tapes are applied to the frame at the top and bottom, in this manner, and the free ends are drawn so as to pull the flexible covering or curtain taut, the free ends of the tapes will be pressed tightly against the face or faces of the frame and be frictionally held against pulling out through the slots. Consequently, the top and bottom of the curtain or covering 10 may be quickly attached to the frame and the curtain or covering may be drawn taut to follow the contour of the frame and have the appearance of hanging in folds.

In the construction shown, the cover is in 15 the form of a continuous element wrapped around the frame or core and having its meeting ends lapped and secured together by snap fasteners or other suitable means, as indicated at 10.

20 It will of course be understood that the construction shown is one in which all of the features of my invention are combined and used to the exclusion of other means adapted for the same general purpose, and that such 25 complete combination or use is not essential, considering the invention broadly. In any event, it will be seen that I have provided a simple and effective fastening device between two members, particularly adapted to secure 30 and hold taut a curtain or other flexible sheet, as well as a novel type of door or curtain regardless of the exact type of fastenings employed and regardless of the structural characteristics of the core or frame or the 35 extent to which the curtain covers the latter.

While I have illustrated and described 40 with particularity only a single preferred form of my invention, I do not desire to be limited to the exact structural details thus 45 illustrated and described; but intend to cover all forms and arrangements which come within the definitions of my invention constituting the appended claims.

I claim:

45 1. In combination, a supporting member having openings therethrough near opposite edges; a second member extending across one side of the supporting member into the vicinity of said openings; and flexible elements connected to said second member and each extending over one of said edges, threaded through the corresponding opening, and having its free end lying between the supporting member and the second member and held in contact with the supporting member by said second member; whereby said second member is secured to the supporting member and subjected to stretching stresses when the free ends of said flexible elements are pulled to 50 draw the flexible elements taut.

55 2. In combination, a supporting member having distributed openings near one edge, a curtain extending across one side of said member, flexible elements secured to said curtain and extending over said edge and back

through said openings, the free ends of said elements lying in contact with said side of said member and being pressed against the same by the curtain.

3. In combination, a supporting member 70 having distributed openings therethrough near opposite edges; a curtain extending across one side of the said member; and flexible elements connected to said curtain in the vicinity of said edges; said flexible elements 75 extending over the corresponding edges of said supporting member and being threaded through said openings so as to position their free ends between and in frictional contact with the supporting member and the curtain. 80

4. In combination, a supporting member having distributed openings therethrough near opposite edges; a curtain extending across one side of the said member; and tapes 85 connected to said curtain in the vicinity of said edges; said tapes extending over the corresponding edges of said supporting member and being threaded through said openings so as to position their free ends between and in frictional contact with the supporting 90 member and the curtain.

5. In combination, a frame having distributed openings therethrough near opposed edges, a curtain extending across the frame, 95 tapes secured to the curtain near said edges of the frame, said tapes extending over the corresponding edges of the frame and their free ends being threaded through the corresponding openings and extending inwardly therefrom between the frame and the curtain and held against the frame by the curtain. 100

6. A device of the character described, comprising a frame having a waved contour on one side, and a curtain extending across 105 said side and secured to the frame in the valleys in the waves therein so as to have the appearance of hanging in folds.

7. A device of the character described, comprising a frame having vertical members 110 and top and bottom cross members, said cross members having faces in the form of waves succeeding each other from end to end of the cross members, and a curtain covering a side of the frame and connected at the top 115 and bottom to the low points in the cross members, whereby the curtain is fixed in position so as to have the appearance of hanging in folds.

8. A device of the character described; a 120 rectangular frame, a flexible sheet extending across the broad faces and two vertical edges of the frame, the broad faces of the frame being shaped to give to the sheet the appearance of hanging in folds when the sheet follows the contour thereof, and fastenings between the top and bottom of the curtain to cause it to follow said contour. 125

9. In a device of the character described, a frame comprising uprights and top and 130

bottom cross members, said cross members having double walls corrugated to form waves whose lengths extend in the vertical direction, a flexible covering for the frame, 5 and means securing said cover to the cross members in the valleys of the waves to cause the cover to follow the contour of said cross members.

In testimony whereof, I sign this specific-
10 cation.

CARL H. NORDELL.
